Specification for Design.

Patented Sept. 7, 1915.

Application filed June 19, 1915. Serial No. 35,174. Term of patent 3½ years.

To all whom it may concern:

Be it known that I, LEWIS A. MAPEL, a citizen of the United States, residing in the city of St. Louis and State of Missouri, have invented a new, original, and ornamental Design for a Toy, of which the following is a specification, reference being had to the accompanying drawing, forming a part thereof.

The drawings illustrate a toy showing my new design, in which drawings,

Figure 1 is a front elevation, Fig. 2 is a rear elevation, and Fig. 3 is a side elevation.

I claim:

The ornamental design for a toy, as shown.

In testimony whereof, I have signed this specification in the presence of two subscribing witnesses, this 18th day of March, 1915.

LEWIS A. MAPEL.

Witnesses:

JOHN D. RIPPEY,
R. M. LAWRENCE.
